Carl Gauschmann

UNITED STATES PATENT OFFICE.

CARL GAUSCHEMANN, OF FRANKFORT-ON-THE-MAIN, GERMANY.

SMELTING FURNACE.

Application filed August 24, 1920. Serial No. 405,770.

To all whom it may concern:

Be it known that I, CARL GAUSCHEMANN, a citizen of the German Empire, residing at Frankfort-on-the-Main, Germany, have invented certain new and useful Improvements in Smelting Furnaces (for which I have filed applications in Germany, September 9, 1915, Pat. No. 295,739, and Febr. 11, 1917, Pat. No. 301,010; Sweden, June 20, 1920; Denmark, June 29, 1920; Norway, June 29, 1920, Pat. No. 32,964; France, July 2, 1920, Pat. No. 518,721; England, July 9, 1920, Pat. No. 147,952; Hungary, July 10, 1920, Pat. No. 80,690; Italy, July 1, 1920, Pat. No. 291/282; Belgium, July 7, 1920, Pat. No. 288,807), of which the following is a specification.

My invention refers to furnaces and more especially to a portable furnace adapted for use in smelting easily fusible metals.

In the furnace according to the present invention easily fusible metals such as lead or tin can be recuperated from waste materials or sweepings by melting in a continuous operation and the furnace can be permanently charged afresh while in action as well as also be discharged of the material melted out.

In the drawings affixed to this specification and forming part thereof two modifications of a furnace embodying my invention are illustrated by way of example. In the drawings:

Figs. 1 and 2 are longitudinal sections at right angles with one another, and

Fig. 3 is a horizontal section of the one modification, whilst

Figs. 4 and 5 are longitudinal sections at right angles with one another and

Fig. 6 the pertinent horizontal section of the second modification.

In all the figures 1 is the mantle of the furnace consisting of four plates fastened together by screws. It is closed at the top by a cover plate 2 provided with a flue connection 3 for the smoke and the waste gases. The firebox 4 proper is lined with masonry. 5 is the grate and 6 is the ash-pan. The melting-pan 7 is arranged above the firebox 4 and hung in special brackets on the wall of the furnace or fastened in some other suitable manner. At its lowest point the melting-pan illustrated in Figs. 1 to 3, is provided with a discharging hole, prefer-

ably covered with a grate 8, a drain 9 leading towards the exterior being connected to it. The melting pan 7 does not extend right to the back wall of the furnace, but leaves a flue channel open there which is covered by a deflecting arch 10. The melting pan is further provided with lateral recesses or passages 11 for the heating gases which are led upwards through special channels 12. Above these channels deflecting hoods 13 are provided, the said hoods protecting the channels from being blocked up or dislocated by the raw material charged into the melting pan. The melting pan might however, also touch the back wall of the furnace in which event additional supports for the pan would be provided and the rear flue channel would be formed by a recess or an opening in the melting pan similar to that marked 11 and roofed over by the arched piece 10. The front wall of the furnace is provided with the cooling door 14 as well as a door 15 for discharging or removing the slags, said door being fitted with an upright grate 16, on a level with the melting pan 7, and furthermore, above these doors, with a door 17 for purposes of observation. The cover plate 2 has a flap 18 through which the material to be smelted is charged into the furnace.

The drain 9 projects a little over the wall of the furnace, so as to allow a crucible or the like to be placed beneath it in order to receive the smelted metal. The working of the furnace is continuous, and not subject to interruptions of any kind either during charging or whilst tapping off the slags.

The operation of the furnace is as follows:

After starting the fire in the fire-box, the melting-pan 7 is charged with raw material through the flap 18. The heating gases are caused to sweep over the melting-pan and owing to the provision of the flue-channels, to pass through the material heaped up upon it. By this means the easily fusible metal melts and flows downwards and outwards through the drain 9 into a crucible placed underneath. The smelting process can be watched through the door 17, which also allows of stirring the charge periodically by means of a stirrer. After one charge is thoroughly melted, the melting-

pan is discharged of its residues through the door 15 and by opening the grate 16. The pan can be recharged immediately, without it being necessary to extinguish or reduce 5 the fire in the furnace. Apart from the short periods of tapping the slags the smelting process can therefor be carried on without interruption.

In the second modification the melting-pan can be tilted from outside for the purpose of emptying it, as well as to hold back 10 the impurities floating on the smelted metal, whilst pouring out.

In Figs. 4 to 6 which illustrate this type 15 of furnace, 7 is the melting-pan which in this case is surrounded by four side-walls and provided with a floor slanting on both sides.

The groove in the floor created by the 20 slanting form of the pan is extended so as to form a drain 19 for pouring out which passes through the corresponding wall of the furnace, the said drain being connected with the interior of the pan by means of a 25 small aperture 20 provided in the front wall of the pan. In front of the forward wall of the pan the drain 19 possesses a convexity 21 in its floor which in tilting acts as a dam and over which the metal must flow in 30 being poured out, the metal being dammed up behind it to such a height that the impurities floating on it are retained by the front wall of the pan. On its outside wall in question is provided with a suitable bearing 22 which contains the journal 23 of the melting-pan, the said journal being pierced 35 through the drain 19. The aperture in the wall must be dimensioned so as to render an oscillating motion of the drain 19 possible.

In the normal position of the smelting-pan as indicated by full lines in Fig. 4, the smelting pan is inclined towards the rear so that a certain amount of metal can always 45 collect. The pan is suspended in this position by means of rods 24 which are attached to the back wall of the pan on the one hand and to levers 25 of a shaft 26 which traverses the upper part of the furnace on the other hand. Outside the furnace the shaft 26 is 50 provided with a suitable mechanism which makes it possible to partially rotate the shaft and thereby tilt the pan. In the example shown in the drawing a lever 27 with 55 a locking device of a well known kind is fitted on the shaft 26. The locking device consists of a notched disk fitted rigidly to the wall of the furnace and of a spring loaded connecting-rod with an engaging catch 60 and a small clasp handle.

In the place of this mechanism any other known kind may also be employed. The one illustrated not only makes it possible to keep the melting pan in any inclined position without trouble, but also allows of re-

turning it quickly into the normal position, if the operation of pouring out is to be interrupted suddenly.

In order to lead the waste gases of the furnace past and at a suitable distance from 70 the doors the roofing of the furnace is made slanting on all sides and the flue connection is arranged in the center directly over the melting-pan.

By moving the lever 27 into the position 75 shown in dotted lines in Fig. 4, the melting pan 7 is carried into the pouring out position indicated by dotted lines, whilst it returns to its starting position, when the said lever is moved back.

I claim:

1. In a device of the kind described in combination, a furnace mantle, a melting pan surrounded by said mantle, flues for compelling the ascending heating gases to flow from above towards said pan, deflecting hoods above said flues, means for charging said pan from above and an opening, adapted to be closed, in said mantle in front of said pan.

2. In a device of the kind described in combination, a furnace mantle, a melting pan surrounded by said mantle, means for tilting said pan from outside, means for conducting heating gases towards and past said pan, means for charging said pan from above and an opening adapted to be closed, in said mantle in front of said pan.

3. In a device of the kind described in combination, a furnace mantle, a melting pan surrounded by said mantle and inclined towards the rear, means for tilting said pan from outside, means for conducting heating gases towards and past said pan, means for charging said pan from above and an opening, adapted to be closed, in said mantle in front of said pan.

4. In a device of the kind described in combination, a furnace mantle, a melting pan surrounded by said mantle, the bottom 110 of said pan slanting from the sides towards the centre, a drain integral with said pan being directly connected to said bottom and projecting through said mantle, means for compelling the ascending heating gases to 115 flow from above towards said pan, means for charging said pan from above and an opening, adapted to be closed, in said mantle in front of said pan.

5. In a device of the kind described in 120 combination, a furnace mantle, a melting pan surrounded by said mantle, the bottom of said pan slanting from the sides towards the centre, a drain integral with said pan being directly connected to said bottom and projecting through said mantle, said pan being adapted to be tilted about the point of contact between said drain and said mantle, means for conducting heating gases towards 125 and past said pan, means for charging said 130

pan from above and an opening, adapted to be closed, in said mantle in front of said pan.

6. In a device of the kind described in combination, a furnace mantle, a melting pan surrounded by said mantle, the bottom of said pan slanting from the sides towards the centre, a drain integral with said pan being directly connected to said bottom and projecting through said mantle, said pan being adapted to be tilted about the point of contact between said drain and said mantle, an axle being laid across said mantle, means for suspending said pan from said axle, means for oscillating said axle from outside, means for conducting heating gases towards and past said pan, means for charg-

ing said pan from above and an opening, adapted to be closed in said mantle, in front of said pan.

20

7. In a device of the kind described in combination, a furnace mantle, a melting pan surrounded by said mantle and inclined towards the rear, means for tilting said pan from outside, a small aperture in the front wall of said pan, a drain integral with said pan in front of said aperture and projecting through said mantle, means for conducting heating gases towards and past said pan, means for charging said pan from above and an opening adapted to be closed, in said mantle in front of said pan.

25

In testimony whereof I affix my signature.

CARL GAUSCHEMANN.
